METAL BOAT HULL CONSTRUCTION

Marcus A. Hall, Bethany, Conn., assignor, by
mesne assignments, to Steelcraft Boats, Incorporated, a corporation of Connecticut

Application September 14, 1944, Serial No. 554,024

14 Claims. (Cl. 9—6)

1
This invention relates to boat hulls, and more particularly to boat hulls constructed of metal such as steel. The invention also relates more particularly to the hull structure of a boat of the speed-boat type, but the invention is not limited to that particular application.

One of the objects is to provide an improved metal hull structure.

Another object is to provide an improved structure in which the hull consists essentially of longitudinal members of a rail-like character, and steel plates applied to those members exteriorly and connected thereto by continuous welds.

Another purpose of the invention is to make the hull very strong, while at the same time the cost of the hull is decreased.

Another object is to provide an improved chine structure for metal boats, and also an improved keel structure.

To these and other ends the invention consists in the novel features and combinations of parts to be hereinafter described and finally pointed out in the claims.

In the accompanying drawings:

Fig. 1 is a side elevation of a boat hull embodying my improvements;

Fig. 2 is a top plan view of the same;

Figs. 3, 4, 5 and 6 are respectively sections on lines 3—3, 4—4, 5—5, and 6—6 of Fig. 1;

Fig. 3A shows on a larger scale certain of the parts shown in Fig. 3;

Fig. 7 is a detail section of the keel portion; and

Figs. 8 and 9 are detail sections of the chine portion.

In the example selected for illustration in the drawings, the hull is one suitable for a speed boat having a length of say 26 feet, this dimension, however, being given only by way of example. The hull is constructed for the greater part of steel plate members, bent to the required shape and welded in place. The hull is shown as equipped with an inboard motor, but the boat may if desired be driven by an outboard motor. In general, the hull is characterized by a high and wide bow usual in speed boats, the bow having a covered deck, and rearwardly of the deck an open cockpit. Along the sides of the cockpit in this example are continuations of the forward deck plate.

In the drawings, transverse sections of the hull are shown in Figs. 3, 4, 5 and 6, the first of these being taken near the stem, the second through the wide portion of the bow, the third through a narrowing portion of the cockpit, and the last (Fig. 6) being taken at a point near the

stern. From these it will be seen that near the stem the hull is characterized by a high and narrow shape, generally triangular, widening out into the shape of Fig. 4 with a flattening of the bottom. In Fig. 5 the V of the bottom has further flattened, the side walls are shorter, and have less angle to the vertical. In Fig. 6 the bottom is further flattened, the side walls are further shortened, and the angles of the side walls to the vertical are reverse angles as compared to Fig. 5.

This hull comprises essentially a deck plate 10 of metal such as steel, side plates 11 and 12, and bottom plates 13 and 14. The plates referred to may be continuous from stem to stern, that is to say, in one piece, or these plates can be made of sections suitably interconnected end-to-end as by welding. The several plates are applied to longitudinal members generally in the nature of rails, extending from stem to stern, or substantially so, and are applied to said members exteriorly and fastened thereto by continuous welds. These longitudinal rail-like members include first, the member 15 which is the keel member, and second, the members 16 and 17 which are chine members. Also included are members 18 and 19 which serve to interconnect the deck plate 10 with the side plates 11 and 12, and are of the nature of sheer and fender members. The keel member is shown in detail in Fig. 7, this section being taken at about the line 5—5 of Fig. 1. Figs. 8 and 9 are details of one of the chine members, Fig. 8 being a section taken approximately at line 4—4 of Fig. 1, and Fig. 9 being a section approximately at line 5—5.

The bottom plates 13 and 14 are connected to the keel member 15 by continuous welds. Fig. 7, for example, illustrates the keel member as comprising a vertical plate portion 15', and integral therewith an upwardly facing channel portion 15''. The channel portion 15'' is preferably of approximately the same thickness as the plate portion 15', and it is preferably approximately semi-circular in cross section, being provided upon its exterior with a smooth generally cylindrical surface 20 which serves for the attachment of the edge portions of the bottom plate members. These bottom plate members abut at their edges against the cylindrical or arcuate surface of the channel and are welded to the member by metal at the edge portions of the plate providing continuous welds 21. As will be apparent, the plates meet the channel member at different angles at different points lengthwise of the hull, but the plates impinge against the channel tangentially at all of these points, and notwithstanding the

fact that, owing to the changing cross section of the hull there are a multiplicity of angles, the plate is effectively connected to the keel member at all these points. As the bottom of the hull becomes flatter, the connection of the plate to the channel member is made farther down on the channel member. This is indicated in Fig. 7, where the full lines show the structure where the bottom is flat, and the dotted lines show the side plates at a point nearer the bow. The lower edge of the plate is in biased or inclined relation to the axis or longitudinal line of the keel member and its channel.

In general the method of connecting the plates to a chine member is similar to that of connecting the plates to the keel member. The chine member 17 (Fig. 8) has applied to it by a continuous weld 22 the bottom plate 14 and the side plate 12. The member 17 is a continuous sheet metal member of angular cross section, the cross section preferably being, as shown, that of a V having a rounded-over apex. The V is arranged with its apex directed outwardly with respect to the hull, and the plates at the respective sides are welded to the side walls of the V. As in the case of the keel member, the points of attachment of the plates to the chine member vary as the cross section of the hull varies. It will be noted that in Fig. 8, for example, the chine member projects laterally to a considerable extent beyond the adjacent plate members, thus providing a spray rail in this portion as well as a structural chine member. The spray rail portion of the chine, that is to say, the portion having this projecting position, runs from a point near the stem preferably to a point somewhat rearwardly of section line 4-4. The projection of the rail then ceases, or at any rate any substantial projection ceases, and the condition then is as shown in Fig. 9, where the intersection of the planes of the two hull plates coincides approximately with the apex of the chine rail. This condition is generally similar in the section shown in Fig. 6, where, however, the angle between the side plate and the bottom plate is somewhat different, being an acute angle rather than an obtuse angle. In general it may be said that the plates extend farthest down on the chine in the section of Fig. 6, that is, they extend closest to the apex of the V, whereas in the section of Fig. 3 they are farthest from the apex. It will be observed also that where a weld is far away from the apex it may have a considerable angle to the median plane of the chine member, as represented at the upper part of Fig. 8, for example. As the bottom of the hull flattens, the bottom plate is drawn closer to parallelism with the median plane of the chine. Generally speaking, the median plane of the chine presents an acute angle to the vertical median plane of the hull, and in this embodiment the first-mentioned angle is approximately constant throughout the length of the hull, although if desired variation may be made in this respect. While the angle of the median plane of the chine remains approximately constant, as just stated, the angles of the hull plates associated with the chine (with respect to a given vertical plane) differ in the various transverse sections of the hull, the plates being attached to the chine at these various angles, as has been brought out in the preceding description.

Referring now to the elongated members 18 and 19, these are further members serving for the interconnection of hull plates, as they serve to secure the side plates 11 and 12 to the deck plate 75.

10. In this case also the connection of the plate to the elongated member is made by a continuous weld, the plate being applied to the exterior of the elongated member. In the particular form shown 5 the member 18 may be taken as an example of the upper rail member, and this comprises a sheet metal member of U shape, presenting a channel. In the present case a lip 18', integrally formed with the rail member on the lower flange or side, has a generally depending position. The rail 19 is similarly formed, having a lip 19'. Each of these U-shaped rail members has its open portion innermost, and the median plane of the U is, in general, horizontally directed, as will be seen from the various sectional views, the median plane being approximately constant in its relation to the vertical throughout the length of the hull, as in the case of the chine members. The deck plate 10 rests on the upper flange or wall 15 of the rail, and is welded thereto by a continuous weld similar to the welds previously described, and at different positions lengthwise of the hull the deck plate has substantially the same general relation to the rail. However, in the case of the 20 side plates of the hull the relation to the rail changes as the inclination of the side plates changes. Thus it will be seen from Fig. 3 that the side plates, where they are welded to the rail, abut the body of the rail at some distance outwardly from the lips 18', 19', whereas in the section shown in Fig. 4 the lips 18', 19' are made use of to the extent that in making the weld the side plates at their edge portions are engaged with and lapped over the lips 18', 19'. A somewhat 25 similar condition is shown in Fig. 5, although in this instance the side plates are more nearly vertical and the lips on the upper rails have been bent into a more nearly vertical location for the purpose of making a proper lap joint. When the 30 section of Fig. 6 is reached, the lips have been further bent in order to be in proper relation to the side plates.

It will be noted further that the rails 18 and 19 35 act as combined sheer and fender members. They are sheer members because they aid in determining the sheer of the side plates, holding the latter in the desired sheer angles. They are fender members because they project laterally beyond the lines of the hull body, so as to act 40 as bumpers in fending off the boat from a pier or the like. In the stem portion of the hull, as shown in Fig. 3, there is no lateral projection of these rails, but in a region intermediate the section lines 3-3 and 4-4 the projection of the rail, 45 in the manner stated, commences, and it will be evident that in the section of Fig. 4 the fender function is realized. This fender portion of the rail continues substantially to the stern, as will be evident from Figs. 5 and 6. In the case of the 50 sheer portion, as well as the chine and keel portions, an elongated longitudinal rail member of bifurcated cross section extends lengthwise of the hull, and plate members are adjacent opposite margins of the rail member and are applied to 55 said member at the exterior of the rail member by continuous welds along the edge portions of the plate members, so as to leave a portion of the rail member exposed, at least one of the plate members having different angular relationship 60 to the vertical at different points lengthwise of the hull, and having its welded edge at an inclination or bias to the longitudinal axis of the rail member so as to be spaced at varying distances from one of the margins of said rail member. 65 It will be manifest from the foregoing descrip-

tion that the improved hull structure is characterized by great simplicity, inasmuch as a substantially complete hull is provided by the keel member, the chine members, the upper rail members, the side and bottom plates, respectively, and the deck plate. The construction described, involving the plate members fastened to the described rail members, is one having great strength. The rail members are of such cross section as to have great strength in themselves. The keel member can be considered broadly as a rail member. The plates are attached to these various rail members at different angles, the angles usually varying continually lengthwise of the hull. The result is that, in the case of any given plate, its general plane is constantly changing lengthwise of the hull, which means that the plate as attached in place has a twist in respect to a theoretical longitudinal axis, placing the plate body in a multiplicity of different planes, the plate being held against two rail members while in this condition, and welded thereto. By this condition the hull is given a surprising amount of strength, so that it resists very effectively stresses in any and all directions. Also as a result of this condition it is possible to use relatively light rail members, the rail members being much lighter than would otherwise be the case. In this method of construction there is obvious cooperation of the forked or bifurcated rail members and the plate members in giving the hull strength and rigidity with the use of a minimum amount of metal, whereby the lightness of the hull is increased greatly in comparison to prior metal hull structures.

It will be understood that while in the hull above described there is an entire absence of inner frame members, inner members can be used if desired for imparting additional strength in certain cases. Also it will be understood that bulkheads, partition members or the like can be used if desired. For the sake of simplicity, however, such members are not shown in the drawings.

It will be evident that by the use of a chine rail such as described, a portion of the rail is especially well adapted to act as a spray rail, inasmuch as the lower flange portion or furcation of the rail is approximately horizontally disposed and in a laterally projecting position so as to cause the spray to be thrown to one side. The rounded apex portion of the rail is also of advantage because it does not create a sharp projection upon the exterior of the hull. The divergent side walls of the chine rail are also of advantage inasmuch as they enable the bottom plates and the side plates to be fastened in place in various positions and at various angles of inclination to the vertical.

I do not claim specifically herein the particular form and arrangement of the sheer rail, as this is claimed in my companion application, Serial No. 554,025, filed September 14, 1944, and patented February 15, 1949, as Patent No. 2,461,819.

While only a single embodiment of the invention is shown in the drawings, it is to be understood that the invention can be embodied in many different forms, and that various changes in the organization of parts and in the details can be made without departing from the principles of the invention or the scope of the claims.

What I claim is:

1. In a boat hull, the combination of an elongated longitudinal rail member of bifurcated

cross section extending lengthwise of the hull, and plate members adjacent opposite margins of said rail member and applied to said member at the exterior of the rail member by continuous welds along the edge portions of the plate members so as to leave a portion of the rail member exposed, at least one of the plate members having different angular relationship to the vertical at different points lengthwise of the hull and having its welded edge at an inclination or bias to the longitudinal axis of the rail member so as to be spaced at varying distances from one of the margins of said rail member.

2. In a boat hull, the combination of a rail member shaped to form a keel, rail members shaped to act as chines, rail members shaped to act as sheer members, bottom plates applied externally by welds to the keel member and the chine members, and side plates applied externally by welds to the chine member and to the sheet members, the bottom plates and side plates being held in position under twist about longitudinal axes, the shape of the hull merging from a wide high bow cross section to a shallow substantially flat-bottomed section adjacent the stern, the chine members being of substantially V cross section and having their apices located toward the exterior of the hull, said chine members having projecting portions adjacent the bow in order to act as spray rails.

3. A boat hull having longitudinal hull plates disposed at different angles to the vertical and different elevations and having adjacent side margins spaced from each other, and an elongated longitudinal rail member to which said side margins are applied exteriorly by continuous welds at the edges of the plates with a portion of the rail member exposed, said rail member being bifurcated in cross section and the plates being applied to the respective furcations, at least one of said plates having its welded edge biased with respect to the longitudinal axis of the rail member.

4. In a boat hull, an elongated generally straight keel member having a plate and integral with the plate at the upper part thereof a channel having a convex outer surface, and a bottom plate for the hull set at an inclination so as to have an upper edge and a lower edge, said lower edge engaging said convex outer surface along a line inclined with relation with the longitudinal axis of the keel member and welded to said convex surface.

5. In a boat hull, the combination of a chine member, a bottom plate supported by said chine member, and a side plate supported by said chine member, said chine member being of substantially V cross section and having its apex located toward the exterior of the hull, the bottom plate and side plate being attached to the chine member progressively farther away from its apex in the forward portion of the hull.

6. In a boat hull, a rail member shaped to act as a chine, a bottom plate supported by said member, and a side plate supported by said member, said chine member being of substantially V cross section and having its apex located toward the exterior of the hull, the chine member being projected from the hull in the bow portion, said plates being welded to the chine member adjacent its apex in the stern portion of the hull, and the side plate in the stern portion of the hull sloping upwardly and inwardly.

7. In a boat hull, a keel member having an integral channel at the upper part thereof, said

channel having a convex outer surface, and longitudinal bottom plates for the hull welded to said convex surface at edges of said plates which are adjacent said surface, said edges being placed higher on the keel member in the direction of the bow.

8. In a boat hull, a keel member having an integral channeled upper portion, a pair of chine members of substantially V cross section having their apices located toward the exterior of the hull, and bottom plates having longitudinal edge portions welded to the channeled portion of the keel member and to the chine members, said plates being placed farther away from the apex of the chine member in the direction of the bow.

9. In a boat hull, the combination of an elongated rail member extending lengthwise of the hull, and plate members adjacent opposite margins of said rail member and applied to the rail member at the exterior of the rail member by continuous welds along the edge portions of the plate members so as to leave a portion of the rail member exposed, at least one of the plate members having different angular relationship to the vertical at different points lengthwise of the hull, said rail member being of bifurcated cross section, and said last-named plate member having its edge portion adjacent the rail member set at an inclination with respect to the longitudinal axis of the rail member.

10. A boat hull having a side plate and a bottom plate joined together at their meeting edges by a welded lap joint, said lap joint comprising a rib generally V-shaped in cross section extending outwardly along the lower edge of the side plate with its apex merging substantially flush with the hull side at the stern of the hull, and gradually extending outwardly from the side of the hull toward the bow and being substantially the full length of the V shape amidship and a lesser amount at the bow, and the adjacent edge of the bottom plate overlapping the lower arm of the V shape and being welded thereto.

11. A boat hull as defined in claim 10, in which the V-shaped rib is disposed along the adjacent edge of the bottom plate and welded to the edge of the bottom plate and in which the side plate is welded to the upper arm or wall of the V shape.

12. A boat hull as defined in claim 10, in which the rib extends outwardly along an edge of the bottom plate which is upwardly disposed with the apex of the rib merging substantially flush with said upper edge at the stern of the hull.

13. In a boat hull, the combination of an elongated longitudinal rail member of a bifurcated cross section extending lengthwise of the hull, and plate members adjacent opposite margins of said rail member and applied to said member at the exterior of the rail member by continuous welds along the edge portions of the plate members so as to leave a portion of the rail member exposed, at least one of the plate members having different angular relationship to the vertical at different points lengthwise of the hull and having its welded edge at an inclination or bias to the longitudinal axis of the rail member so as to be spaced at varying distances from one of the margins of said rail member, said rail member having the cross section of a V whose walls are at substantially less than 90° to each other.

14. In a boat hull, the combination of an elongated longitudinal rail member of a bifurcated cross section extending lengthwise of the hull, and plate members adjacent opposite margins of said rail member and applied to said member at the exterior of the rail member by continuous welds along the edge portions of the plate members so as to leave a portion of the rail member exposed, at least one of the plate members having different angular relationship to the vertical at different points lengthwise of the hull and having its welded edge at an inclination or bias to the longitudinal axis of the rail member so as to be spaced at varying distances from one of the margins of said rail member, said rail member having a cross section in the shape of a U.
